UNITED STATES PATENT OFFICE.

FRANK WYLDE BALL, OF MELBOURNE, VICTORIA, AUSTRALIA.

ELECTRICAL HEATING UNIT.

1,119,336.

Specification of Letters Patent.

Patented Dec. 1, 1914.

Application filed August 26, 1914. Serial No. 858,684.

To all whom it may concern:

Be it known that I, FRANK WYLDE BALL, of 380 Flinders street, Melbourne, in the State of Victoria, Commonwealth of Australia, have invented certain new and useful Improvements in Electrical Heating Units, of which the following is a specification.

This invention relates to an improved electrical heating unit and method of manufacturing the same and has been devised particularly for use in ovens, soldering irons, radiators, hot-plates, and similar industrial and domestic articles.

A heating unit constructed according to the present invention will be exceedingly simple and durable in construction and can be very economically constructed in a variety of forms to suit the different purposes to which it is adaptable.

In order that the invention may be readily understood reference will now be had to the accompanying sheet of explanatory drawings, wherein:

Figure 1 is a view in side elevation of an electrical heating unit constructed according to the present invention. Fig. 2 is a longitudinal sectional elevation of Fig. 1, omitting the high resistance wire. Figs. 3, 4 and 5 are views partly in section and partly in elevation of modified forms of the invention and hereinafter are fully described.

In these drawings like characters of reference have been employed to indicate similar or corresponding parts in the different views and the letter *a* designates a tube of pure quartz which is mounted on a metallic rod *b* of suitable diameter and shape. The hole in the quartz tube *a* is made to correspond to the shape of the rod *b* and the said tube is arranged to slide freely over the said rod. The quartz tube *a* is retained in its correct position on the rod *b* by nuts *c* keys, pins or the like and its periphery is provided with a helically cut groove *d* of preferred shape to take a high resistance wire or ribbon *e*. The high resistance wire or ribbon *e* is wound in the helically formed groove *d* and one of its ends is secured to an end of the centrally disposed metallic rod *b* and the opposite end is secured to a ring or ferrule *f* secured to the other end of the quartz tube. The ferrule *f* and concentrically disposed end of the metallic rod *b* are arranged to contact with a concentric plug of approved construction (not shown) furnished with

lead and return wires respectively disposed in the most approved way to suit the construction of article or utensil to which the invention is fitted. One or more windings 60 or layers of mica *g* or other non-conducting material is interposed between the rod *b* and the quartz tube *a* so as to further increase the insulating effect.

In lieu of employing a solid metal rod *b* 65 for a return lead through the quartz tube *a* a tubular rod *h* can be used and water or other liquid can be passed therethrough to be heated for any purpose desired.

The quartz tube *a* can be made of any 70 convenient length and if preferred two or more lengths placed end to end on the rod *b* can be employed to form each heating unit.

i indicates a tubular covering which is preferably of quartz and is placed over the 75 quartz tube *a* while a layer of mica *j* or other suitable non-conducting material can be interposed between this covering and the tube *a*.

The tubular covering *i* is retained in position on the quartz tube *a* by a flange *k* on the ferrule *f* and a washer *l* on the opposite end of the rod *b*. The ferrule *f* is retained fixedly in position on the quartz tube *a* in an approved manner as by pressing a 85 tongue *m*, formed on the former, into a recess *n* formed in the latter.

A modification of the invention is shown in Fig. 4 of the drawings and consists in arranging a plurality of interfitting tubes *o* 90 over the tube *a*. These tubes *o* are provided with helical grooves on their peripheries to accommodate a high resistance wire *e*.

In winding a unit of this construction the wire *e* is wound in the groove in the tube *a* 95 and then the first tube *o* is slid thereover after which the wire is wound in the opposite direction in the groove formed therein. When the wire *e* has been wound the full length of the groove in the first tube *o* the 100 second tube *o* is slid thereover and the wire is then wound in the groove formed in its periphery.

If preferred an outer tube *i* of quartz can be employed to cover the groove in the outer tube and the wire wound therein, and a layer of mica *j* or other suitable non-conducting material can be interposed between the tube *o* and covering *i*. The tubes *o* are retained in their correct positions by a flange 110 on the ferrule *f* and a washer *l* on the opposite end of the rod *b*. One end of the wire

e is passed through a hole in the flange on and secured to the ferrule *f* and the other end is secured to the end of the rod *b* located at the opposite end of the unit.

5 The said tube *a* is made by bringing powdered or crushed quartz to a molten state and then casting or molding it to the shape required.

10 The helical groove *d* in the quartz tube *a* is cut with a carborundum stone revolved at high speed and passing backward and forward over the face of the said tubing. If preferred the carborundum stone can be retained in a fixed position and the quartz 15 tubing passed backward and forward in front thereof at a uniform rate of speed. The helically cut groove *d* can be molded in the periphery of the quartz tubing and not necessarily by grinding as before described or it can be formed by spinning a 20 thread helically on the periphery of a plain tube.

What I do claim is:

1. An improved electrical heating unit 25 comprising a supporting rod, a plurality of interfitting tubes of quartz fitting over said rod, said tubes having formed on the peripheries thereof helical grooves, a high resistance

wire wound in the grooves of said tubes and having its end connected to said rod and to a terminal on one end of the inner tube, and layers of non-conducting material arranged around said supporting rod and around the grooved peripheries of the interfitting tubes, substantially as described.

2. An improved electrical heating unit comprising a supporting rod, a plurality of interfitting tubes of quartz fitting over said rod, said tubes having formed on the peripheries thereof helical grooves, a high resistance wire wound in the grooves of said tube, and a tubular covering of quartz and rod and to a terminal at one end of the inner tube, and a tubular covering of quartz and a layer of mica or non-conducting material 4 interposed between said tubular covering and the outer tube, substantially as described.

In witness whereof I have signed this specification in the presence of two witnesses.

FRANK WYLDE BALL.
